Primary Examiner—A. Hugo Word*Assistant Examiner*—I. Simmons*Attorney, Agent, or Firm*—Gary L. Griswold; Walter N. Kirn; Stephen W. Bauer[57] **CLAIM**

The ornamental design for a stylet for retrograde coronary sinus cannula, as shown and described.

DESCRIPTION

FIG. 1 is a perspective view of a stylet for retrograde coronary sinus cannula showing our new design, the shaft of the stylet is shown broken to indicate indeterminate length;

FIG. 2 is a front elevational view thereof;

FIG. 3 is a rear elevational view thereof;

FIG. 4 is a top plan view thereof, the shaft of the stylet is shown broken to indicate indeterminate length;

FIG. 5 is a right side elevational view thereof, the left side elevational view being identical thereto, the shaft of the stylet is shown broken to indicate indeterminate length; and,

FIG. 6 is a bottom plan view thereof the shaft of the stylet is shown broken to indicate indeterminate length.
